6 Claims. (Cl. 83—538)

ABSTRACT OF THE DISCLOSURE

Manual swinging of the beam of a cantilever cutting press is facilitated by supplying fluid, suitably air, under pressure to the bearing of the post on which the beam is supported.

This invention relates to improvements in cutting presses and more particularly to improvements in presses of the type having a swinging beam and commonly known as clickers, the improvement being directed to facilitating the task of the operator in swinging the beam during the course of cutting operations.

The invention is illustrated as embodied in a press of the type disclosed in U.S. Letters Patent No. 3,172,324 issued Mar. 9, 1965, on an application in the name of the present inventor. However, it will be appreciated that the invention is not confined to use with presses of this particular construction.

From a reading of the above patent as well as from other sources of information regarding the manner of operation of such cutting presses, it will be understood that during the course of a day's work in cutting out parts, the operator must swing the beam or beams of a cutting press many times from a cutting position to a rest position in which suitable access to the workpiece and the cutting die is provided for setting up the next cut. Depending on the size and position of the cutting die, the necessary arc of swing can vary from a small angle to as much as 90°. Each time the operator swings a beam he must overcome the static friction between the post on which the beam is mounted and the bearing in which the post is journaled, this static friction being greater after the beam has remained for a time in a given position due to rupture of the oil film where the weight of the beam pulls the post against the wall of the bearing.

Much effort has heretofore gone into making easier the task of the operator in swinging a cutting beam; for example, much design effort has gone into making beams lighter. Further various types of power means for assisting the swinging of the beam have been proposed. As cutting presses of the clicker type have become larger and more powerful, a practical limit appears to have been reached in designing a beam light enough for manual swinging by the operator. On the other hand, the provision of power means for assisting beam swing has the objection of introducing added complication and expense.

Accordingly, it is an object of the present invention to provide, in a cutting press of the type having a cutting bed and a beam carried by a vertical post journaled in a sleeve bearing for swinging over the bed, of means for reducing the effort required to swing the beam during the cutting operation. The bearing is commonly, and as illustrated, rigid with the frame of the press, but it will be understood that the invention is applicable to presses having a fixed post journaled in a bearing rigid with the beam.

To this end and in accordance with a feature of the present invention, the manual swinging of such a beam is facilitated by admitting gaseous fluid under pressure to the

2

space between the post on which the beam is supported and the sleeve bearing in which the post is journaled. The gaseous fluid preferably is introduced into said space at a location wherein it is effective in exerting a pressure against the post in a direction at least partially to offset the weight of the beam in pulling the post to one side of the bearing. However, there is a wide latitude of circumferential location; the application of such fluid under pressure to said space also is effective in reducing starting effort even if applied at a location removed by 90° or more from the axis of the beam. Thus the gaseous fluid appears to have the effect of forcing oil into the area of the bearing where it otherwise might be squeezed out with resulting metal to metal contact. For whatever reasons, however, the provision of such gaseous fluid supply means has proved effective in reducing, to a large extent the effort required to swing the beam.

Preferably, and in accordance with another feature of the present invention to avoid drying out the bearing lubricator, a small amount of lubricant is introduced into said space along with the gaseous fluid.

These and other features and advantages of the present invention will best be understood from the following description taken together with the accompanying drawings

in which:

FIG. 1 is a rear elevation of apparatus embodying the present invention;

FIG. 2 is a plan view of the apparatus shown in FIG. 1;

FIG. 3 is a section taken on the line III—III of FIG. 1
30 on a scale enlarged approximately five times; and

FIG. 4 is a diagrammatic view illustrating certain aspects of the present invention.

Only so much of the illustrative machine as is required to understand the present invention will be described herein; the reader is referred to the above-mentioned patent for further details. Accordingly, referring now to FIGS. 1 and 2 of the drawings, the press shown therein comprises a frame 10 carrying a cutting bed 12 on which the work is supported in cutting out parts. The frame 10 carries at opposite sides of the bed 12 a pair of vertically oriented sleeve bearings 14 and 16 in which are journaled respectively two posts 18 and 20 to which swing beams 22 and 24 are clamped. The beams are thus supported for movement toward and away from the cutting bed in cutting strokes and for swinging about the axes of the posts to the extent permitted by beam swing stops comprising for the beam 22 a blade 26 and stop member 28 (FIG. 1).

Under certain cutting conditions it is necessary for the operator to swing the beams up to 90° from the position when centered over the cutting bed. For example where a large die such as the die 30 is employed, it may be desirable to swing both beams rearwardly by about 90° to provide convenient access for the operator and work in the manipulation thereof.

At the end of a cutting stroke when a post rises to the end of its stroke from its sleeve bearing, the movement of the post in the bearing will have provided a fresh film of oil between the surfaces of the post and the bearing, and if the operator immediately pushes the beam to clear it as he normally does, the static friction will be minimal at this time. However, if the beam remains in one position for any length of time, for example, in the rear position, the effort required to swing the beam is increased. To explain this, I have postulated that in this situation while the operator is rearranging the work, a condition, diagrammed in greatly exaggerated form in FIG. 4, will develop in which the weight of the beam will squeeze out or rupture the oil film, particularly in an area 32 at the upper end of the bearing on the side toward the beam and allow metal to metal contact to take place in this area.

I have found that the effort required to swing a beam

can be greatly reduced by supplying a portion of the space between the inner surface of the bearing and the post a gaseous fluid such as air. Preferably the fluid is supplied together with sufficient oil to maintain an oil film in the critical areas of the mating surfaces of the bearing and post. Where the post and bearing have been pre-lubricated, supplying air alone to the bearing will suffice for a period, but in the long run oil lost through natural escape or through having been expelled by air pressure must be replaced and I prefer accordingly to introduce a small amount of oil with the gaseous fluid supplied to the bearing. I believe, although I do not wish to be limited thereby, that the effect in reducing the starting effort results in part from the force developed by the air pressure against the post tending to counteract the weight of the beam and straightening up the post in the bearing, and perhaps in greater part from the effect of the air pressure in forcing lubricating oil between the opposing surfaces in areas where it will do the most good in preventing metal to metal contact.

Thus means for supplying gaseous fluid and oil to a portion of the space between the post 18 and the sleeve bearing 14 of the illustrative press comprises a pipe-threaded male fitting 50 having a passage communicating through an air port 51 (FIG. 2) formed in the bearing 14 with a portion of the space between the post 18 and the bearing. A flexible tube 52 connects the fitting 50 to a bulkhead fitting 54 supported in a bracket 56 attached to the frame 10 of the machine. The bracket 56 serves to support a drip type oiler 60 the outlet means of which is connected to the fitting 54, a T-fitting 62 and a reducing valve 64 arranged to control the pressure of air supplied to the oiler from a supply means comprising an air hose 66. Corresponding elements on the right presser assembly are indicated by prime numerals. The pressure of the air supplied to the oiler 60 and via a flexible tube 68 to an oiler 60' (FIG. 2) for the other bearing which is correspondingly connected thereto, is indicated by a pressure gauge 72.

The air port 51 may be located circumferentially within a wide angular range. It would seem that if the construction of the cutting press permits, the air port 51 should preferably be located at a point intermediate the extreme positions of the center line of the beam 22, that is within an arc 80, FIG. 3, which indicates the normal arc of maximum swing of the center line of the beam 24. However, although as in the case of the illustrative press, it is not always possible to dispose the fittings with the air port within this arc, I have found that even when the air port is located beyond the normal extreme limit of the beam axis as indicated by the angle 82, the starting effort for swinging the beam back from its operating position is materially lessened by the supply of air at this point. The heightwise location of the air port can be varied within broad limits, but the port should be sufficiently below the top of the bearing to permit the application of an effective air pressure without excessive escape of air and oil at the top of the bearing.

In operation with each of the oilers, 60, 60' adjusted to provide about one drop each three minutes, air is supplied continuously to the admission ports 51, 51' at a pressure

regulated by the valve 64 which pressure, while effective in reducing the necessary swing effort is low enough to avoid excessive escape of air and oil at the top of the bearing. The applied pressure may vary in range from about 10 to about 40 p.s.i. and a suitable pressure will be established by experience with a particular machine. For example, I have found that a pressure of about 10 to 15 p.s.i. is suitable for a press of the type illustrated.

Having thus described my invention, what I claim as new and desire to secure by Letters Patent of the United States is:

1. In a cutting press having a cutting bed and a beam carried by a vertical post disposed at one side of the cutting bed, the post being journaled in a sleeve bearing for swinging of the beam over the bed, in combination therewith, means for supplying to a portion of the space between the inner surface of the bearing and the post fluid at a pressure greater than atmospheric.

2. Apparatus as in claim 1 wherein the fluid is a gaseous fluid.

3. Apparatus as in claim 1 wherein the fluid is a gaseous fluid having entrained therein a relatively small amount of lubricating oil.

4. Apparatus as in claim 1 wherein said fluid is a gaseous fluid, said means for supplying said fluid additionally comprising a drip type oiler for entraining a relatively small amount of lubricating oil in the gaseous fluid supplied to said space.

5. In a cutting press, in combination, a cutting bed, a sleeve bearing disposed with its axis vertically oriented at one side of said bed, said bearing being formed with a radial port, a post journaled in said bearing and a beam carried by said post for movement toward and away from the cutting bed for dieing out work parts thereon and for swinging about said axis and means comprising a conduit connected to said bearing and having a passage communicating through said port with the space between the post and the bearing for supplying fluid under pressure between areas of the inner surface of the sleeve bearing and the outer surface of the post.

6. Apparatus as in claim 5 wherein said fluid supply means additionally comprises valve means operative to regulate the pressure of gaseous fluid supplied to said conduit and means for supplying lubricating oil in controlled amount to said conduit.
